UNITED STATES PATENT OFFICE.

JOHN M. BURKHALTER, OF CANYON, TEXAS.

SLED LISTER CULTIVATOR.

Application filed November 27, 1926. Serial No. 151,152.

This invention relates to a sled lister cultivator and it is an object of the invention to provide a device of this kind wherein the runners are provided at their forward end portions with furrow openers together with a lever operating mechanism readily operable by the occupant of the seat of the device for raising or lowering such openers as the occasion of practice may desire. It is also an object of the invention to provide a device of this kind provided with a rear arch with which is adapted to be associated a ground working element or elements together with a mechanism readily operable by the occupant of the seat of the device for raising or lowering such arch as may be desired.

Another object of the invention is to provide a device of this kind including a vertically adjustable or swinging rear arch with which is operatively engaged a plurality of drag hoes together with means whereby said hoes may be laterally adjusted one with respect to the other as the necessities of practice may require.

The invention consists in the details of construction and in the combination and arrangement of the several parts of my improved sled lister cultivator whereby certain important advantages are attained and the device rendered simpler, less expensive and otherwise more convenient and advantageous for use as will be hereinafter more fully set forth.

The novel features of my invention will hereinafter be definitely claimed.

In order that my invention may be the better understood, I will now proceed to describe the same with reference to the accompanying drawings, wherein:—

Figure 1 is a view in top plan illustrating a sled lister cultivator constructed in accordance with an embodiment of my invention;

Figure 2 is a view in side elevation of the device as illustrated in Figure 1;

Figure 3 is a fragmentary vertical sectional view taken through the forward portion of the cultivator;

Figure 4 is a sectional view taken substantially on the line 4—4 of Figure 3;

Figure 5 is a fragmentary detailed sectional view illustrating the forward end portion of a runner, an associated furrow opener being diagrammatically indicated by broken lines;

Figure 6 is a fragmentary vertical see-

tional view taken through the rear portion of the device as herein set forth;

Figure 7 is a sectional view taken substantially on the line 7—7 of Figure 6;

Figure 8 is an enlarged detailed sectional view taken substantially on the line 8—8 of Figure 6;

Figure 9 is a detailed sectional view taken substantially on the line 9—9 of Figure 8;

Figure 10 is a view in top plan of the plate engaged with the rear arch unapplied.

As illustrated in the accompanying drawings, 1 denotes the runners of a sled lister cultivator, each of which having engaged with the forward portion thereof an outstanding weed cutting blade or knife 2 extending rearwardly on a predetermined outward incline, the under surface of said blade being substantially flush with the under edge face of the runner 1. Associated with the forward extremity of each of the runners 1 is a furrow opener or plow P comprising a plate 3 having its flat faces vertically disposed when in applied position. The rear of the plate 3 is provided with laterally spaced extension plates 4 which are adapted to receive therebetween the forward end portion of a runner 1. These extension plates 4 are pivotally connected to said forward portion of the runner 1 by the bolt 5 or the like whereby said opener or plow P is capable of swinging movement in a vertical direction.

To facilitate the requisite swinging movement of the opener or plow P the outer lower corner of each of the extension plates 4 is cut away, as at 6, while the adjacent end of the runner is outwardly beveled in opposite directions, as at 7.

The forward edge 8 of the plate 3 is disposed on a downward and inward curvature to facilitate the opener or plow P penetrating the soil. Extending upwardly from the plates 3 are the arms 9 held to the outer faces of such plates by the bolts 10. The upper extremities of the arms 9 are continued by the inwardly disposed extension arms 11, one overlapping the other. These extension arms 11 are effectively held one to the other by the U-clamps 12 of a convenient type. The arms 9 with their extension arms 11, when assembled, provide an upstanding arch member connecting the openers or plows P for unitary swinging movement in a vertical direction. The clamps 12 permit relative adjustment of the

extension arms 11 to readily compensate for differing spacing between the runners 1.

Extending upwardly and laterally from the forward portions of the runners 1, and

- 5 herein disclosed as secured to the upper edge faces of the runners 1, are the tables or platforms 14. To these tables or platforms 14 are bolted, as at 15, or otherwise secured the inner portions of the forwardly disposed
- 10 and outwardly inclined strap irons or rigid arms 16. To the outer extremities of these strap irons or rigid arms 16 are bolted, as at 17, the upstanding arms 18 continued at their upper ends by the inwardly disposed
- 15 and overlapping extension arms 19. Selectively disposed through registering openings 20 in the extension arms 19 is a bolt 21. The arms 18 together with the extension arms 19 provide an arch member connecting
- 20 the irons or arms 16 and the bolt 21 permits a relative adjustment of these extension arms 19 to readily compensate for the differing distances between the runners 1.

The bolt 21 is also disposed through the 25 opposed legs 22 of a downwardly facing hook member 23 straddling from above the overlapping portions of the extension arms 19 whereby an effective support is afforded for the forward end portion of a rearwardly disposed elongated arm 24. This arm 24 is of a length to terminate, as herein set forth, substantially midway of the ends of the runners 1 and the rear portion of the arm 24 is connected by the bolt 25 with an 30 upwardly and inwardly inclined supporting member 26. There are two of these members 26, each secured to the table 14 by the bolts 15 hereinbefore referred to and said members 26 below the arm 24 are connected

- 35 by the rigid bracing or reinforcing member 27 bolted, as at 28, or otherwise attached thereto.

The upper portions of the members 26 above the arm 24 are connected by the bolt 45 29 or the like and freely mounted on said bolt 29 and substantially snugly engaging between the adjacent end portions of the members 26 is a sleeve 30 carried by and arranged to one side of the boxing 31 to be 50 hereinafter more particularly referred to.

Interposed between the runners 1 and the upper portions of the members 26 are the brace members or straps 32 the upper portions of which being secured to the members 26 by the bolts 25 and 25'. These brace members 32 extend downwardly and rearwardly on a predetermined incline and are bolted, as at 33, or otherwise secured to the runners 1.

- 55 60 Bolted or otherwise attached, as at 34, to the central portion of the arm 24 is an upwardly disposed arcuate rack 35 having an inwardly and forwardly depending extension arm 36 carried by the rear portion 65 thereof. Pivotally engaged, as at 37, with

this extension arm 36 is the lower end portion of an upstanding lever 38 provided with a conventional latch mechanism 39 coacting with the rack 35.

The lever 38 is disposed through a sleeve 70 40 provided with a forwardly disposed bracket 41 terminating in a laterally disposed barrel 42 through which is directed a bolt 43 or the like. This bolt 43 has pivotally engaged with the extremities thereof 75 the upper portions of the arms 44, the opposite end portion overlapping the inner end portion of an arm 45 pivotally held to the upper portion of the plate 3 by one of the bolts 10 hereinbefore referred to. The overlapping portions of the arms 44 and 45 are connected for adjustment one relative to the other through the medium of the bolt and socket connection indicated at 46.

It is thought to be apparent that upon requisite operation of the lever 38 the openers or plows P will be raised or lowered when desired and that upon relative adjustment 80 of the arms 44 and 45 the depth of penetration of the openers or plows P may be 90 regulated.

In practice, the openers or plows P operate to open the ground or to cut a furrow in advance of the runners 1 so that said runners will drop a desired extent below the 95 normal surface of the land whereby the blades 2 hereinbefore referred to will be caused to work in the subsoil and thereby effectively destroy weeds and the like. This operation, as just stated, is particularly true 100 when working on flat land. When working in lister furrows the plows or openers P operate effectively to break clods or the like which may be within such furrows to assure the cultivator proper running steady 105 and to the best advantage, the openers or plows P being adjusted downwardly in accordance with the extent to which said lister furrows may be filled.

The rear portions of the runners 1 are 110 provided with the upstanding bearings 47 with which are engaged the outstanding trunnions 48 comprised in the upstanding rear arch 50. These trunnions 48 are relatively long in order to compensate for the 115 relative adjustments of the runners 1 with respect to each other. The upper portion of the arch 50 is provided with the forwardly directed U-bracket 51 the side arms of which being connected by a pin 52 or the like.

Pivotally engaged with the pin 52 are the outer extremities of the parallel arms 53 constituting a forked portion of a bar 54. The bar 54 has secured thereto by the bolts 55 or the like the upstanding arcuate rack 56. The rear end portion of this rack is provided with a downwardly and forwardly inclined extension arm 57 to the lower portion 120 of which is pivotally connected, as at 58, the 125

lower extremity of an upstanding lever 59. This lever 59 is disposed through the boxing 31 hereinbefore referred to, said boxing being suitably held in a fixed position upon the lever 59. The lever 59 also carries a conventional latch mechanism 60 for coaction with the rack 56. Upon requisite swinging movement of the lever 59 the rear arch 50 may be raised or lowered as desired and such arch is locked in desired adjusted position by engagement of the latch mechanism 60 with the rack 56.

The seat S, as herein disclosed, is supported by the forked portion 53 of the bar 54 and is held thereto in any preferred manner.

The side arms of the arch 50 have clamped, as at 61, to the rear edge faces thereof the bearing plates 62 with which are operatively engaged the trunnions 63 carried by the forward portion of the plate 64. The plate 64 is disposed rearwardly of the arch 50 and is mounted for swinging movement in a vertical direction. This plate 64 is adapted to have applied thereto any desired type of ground working implement but, as herein disclosed, there is pivotally connected, as at 65, with this plate at transversely spaced points the rearwardly extending beams 66. Each of these beams 66, as particularly illustrated in Figure 6, comprises spaced parallel members integrally connected at their outer portions by the interposed web 67 while their forward or free end portions receive therebetween the plate 64. Contacting with the outer side edges of the beam 66 is the upper portion of the vertically disposed standard 68 the lower portion of which having fixed thereto a drag hoe 69 or other kindred implement. This standard 68 is also disposed through an eye member 70 having a shank 71. This shank 71 is directed between the spaced parallel members of the beam 66 and through the plate 72 bridging the space between said parallel members and contacting with the outer edge faces thereof, as particularly illustrated in Figure 8.

Threaded upon the shank 71 is the holding nut 73 which is adapted to have direct contact with the plate 72 to draw the eye member 70 inwardly of the beam 66 and thus effectively grip the standard 68 and particularly to hold the same between the notches 74 provided in the outer edge faces of the parallel members of the beam 66. In practice, these notches 74 may be spaced as desired lengthwise of the beam 66 so that the desired position of the standard 68 along the beam may be effectively maintained.

The web 67 has held thereto by the holding nuts 75 the forward portion of a rearwardly disposed elongated shank 76 having its outer or free end portion laterally directed, as at 77, and with which laterally directed portion is operatively engaged a

rod 78. This rod has its outer portion overlapping a second rod 79 and said rod 79 effectively coupled through the medium of U-clamps 80. The U-clamps 80 permit relative adjustment of the rods 78 and 79 as 70 may be required. The rod 79 is operatively engaged, as at 81, with the lower portion of an upstanding lever 82. This lever 82 is pivotally connected, as at 83, with an upstanding bracket 84 secured to the rear portion of a runner 1, said bracket being provided with an arcuate rack 85 with which coacts a latch mechanism 86 carried by the lever 82.

The beams 66 have their outer portions 80 connected by a spreader 87 whereby the beams 66 are maintained in desired spaced relation and caused to have unitary lateral swinging movement upon operation of the lever 82. The latch mechanism 86 coacts 85 with the rack 85 to hold the beams 66 in desired selective adjustment.

The spreader 87 comprises two members 88 having their inner portions in overlapping relation with their outer end portions 90 freely engaged with the standards 68. The overlapping portions of the members 88 are adjustably connected through the medium of a bolt and socket connection, as indicated at 89.

To further assure the runners 1 being maintained in desired spaced relation and in parallelism, each of said runners has bolted, as at 90, to the outer face thereof the lower portion of an upstanding arm 91 the upper 100 extremity of which being continued by an inwardly directed extension arm 92. The extension arm 92 of one arm 91 overlaps the corresponding extension arm of the second arm 91 and these extension arms 92 are connected one to the other through the medium of the U-clamps 93. These U-clamps 93 permit ready relative adjustment of the extension arms 92 in accordance with the required spacing of the runners 1. The arms 91 are preferably carried by the runners 1 inwardly of the longitudinal centers thereof whereby effective bracing or reinforcement is provided at the rear.

The runners 1 are preferably of wood and for which reason I find it of advantage to provide the side faces of each of the runners at the forward portions thereof with the metallic wear plates 94 to withstand the action of the extension plates 4 comprised in the 110 furrow openers or plows P.

The pin 52 also has engaged therewith a rearwardly directed hook member 95 with which may be engaged a chain or the like which, when operatively engaged with the beams 66 or their equivalent, will hold the same in a raised or inoperative position.

From the foregoing description it is thought to be obvious that a sled lister cultivator constructed in accordance with my 120

invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. In combination with the runners of a sled cultivator, furrow openers positioned in advance of the runners, each of said openers comprising a plate the inner portion of which being provided with spaced plates to receive therebetween the forward portion of a runner, means for pivotally connecting said spaced plates to the runner, a swinging lever supported by the runners, and a member pivotally engaged directly with the first named plate of each of the openers and with the lever whereby the furrow openers are raised and lowered upon operation of the lever.

2. In combination with the runners of a sled cultivator, furrow openers positioned in advance of the runners, each of said openers comprising a plate the inner portion of which being provided with spaced plates to receive therebetween the forward portion of a runner, means for pivotally connecting said spaced plates to the runner, a swinging lever supported by the runners, a member pivotally engaged directly with the first named plate of each of the openers and with the lever whereby the furrow openers are raised and lowered upon operation of the lever, and an upstanding arch member connecting the first named plates of the openers, said arch being independent of the members pivotally connecting the plates and the lever.

3. In combination with the runners of a sled cultivator, furrow openers pivotally engaged with the forward portions of said runners for movement in a vertical direction, an upstanding arch member operatively supported by the runners, an elongated member, means for supporting one end portion of the elongated member by the arch member, supporting means for the opposite end portion of the elongated member operatively mounted upon the runners, an upstanding arcuate

rack carried by the elongated member, a lever supported for swinging movement with respect to the rack, a latch mechanism carried by the lever coacting with the rack, and members pivotally engaged with the lever and with the furrow openers to raise or lower said openers upon swinging movement of the lever.

4. In combination with the runners of a sled cultivator, furrow openers pivotally engaged with the forward portions of said runners for movement in a vertical direction, forwardly disposed arms carried by the forward portions of the runners, an outstanding arch member secured to said arms, an elongated member, means for supporting one end portion of the elongated member by the arch member, supporting means for the opposite end portion of the elongated member operatively mounted upon the runners, an upstanding arcuate rack carried by the elongated member, a lever supported for swinging movement with respect to the rack, a latch mechanism carried by the lever coacting with the rack, and members pivotally engaged with the lever and with the furrow openers to raise or lower said openers upon swinging movement of the lever.

5. In combination with the runners of a sled cultivator, furrow openers pivotally engaged with the forward portions of said runners for movement in a vertical direction, outstanding platforms carried by the forward portions of the runners, said platforms being substantially aligned transversely of the cultivator, forwardly and outwardly disposed arms carried by the platforms, an upstanding arch member mounted on said arms, an elongated member, means for supporting one end portion of the elongated member by the arch member, supporting means for the opposite end portion of the elongated member operatively mounted upon the runners, an upstanding arcuate rack carried by the elongated member, a lever supported for swinging movement with respect to the rack, a latch mechanism carried by the lever coacting with the rack, and members pivotally engaged with the lever and with the furrow openers to raise or lower said openers upon swinging movement of the lever.

In testimony whereof I hereunto affix my signature.

JOHN M. BURKHALTER.
